DESIGN FOR A DECORATIVE WALL MATERIAL OR THE LIKE

William Burton, Chicago, Ill., assignor to Trimz Company, Inc., Chicago, Ill., a corporation of Delaware

Application October 4, 1944, Serial No. 115,594

Term of patent 7 years

(Cl. D59—10)

To all whom it may concern:

Be it known that I, William Burton, a citizen of the United States, residing at Chicago, in the county of Cook and State of Illinois, have invented a new, original, and ornamental Design for a Decorative Wall Material or the like, of which the following is a specification, reference being had to the accompanying drawing, forming a part thereof.

In the drawing the figure is a plan view of the decorative wall material, showing my new design.

I claim:

The ornamental design for decorative wall
material or the like, substantially as shown.

WILLIAM BURTON.
